UNITED STATES PATENT OFFICE.

MELVILLE A. CLARK, OF SYRACUSE, NEW YORK.

DESIGN FOR A HARP.

41,987.

Specification for Design.

Patented Dec. 19, 1911.

Application filed June 26, 1911. Serial No. 635,482. Term of patent 14 years.

To all whom it may concern:

Be it known that I, MELVILLE A. CLARK, a citizen of the United States, residing at Syracuse, in the county of Onondaga and State of New York, have invented a new, original, and ornamental Design for Harps, of which the following is a specification, reference being had to the accompanying drawing, forming part thereof.

The figure is a side elevation of a harp, showing my new design which consists in the compound-curved downwardly arched neck —*a*— merging at its ends in curved

lines —*a'*— and —*a''*— with an upwardly tapering body —*b*— and a compound-curved pillar —*c*— having a comparatively long outward swell —*c'*—, and strings across a chord of the long swell and intersecting the upper part of the pillar.

What I claim is:

The ornamental design for a harp, as shown and described.

MELVILLE A. CLARK.
